UNITED STATES PATENT OFFICE.

HERBERT C. RYDING AND ARTHUR B. HASWELL, OF BIRMINGHAM, ALABAMA.

HEATING FURNACE.

Application filed April 9, 1926. Serial No. 100,851.

This invention relates generally to improvements in heating furnaces and in particular to an improved form of furnace having a travelling hearth adapted to convey the articles to be treated through the furnace. The invention will be understood from the following specification when read in connection with the accompanying drawings in which—

10 Fig. 1 is a longitudinal section through a furnace embodying our invention;

Fig. 2 is a horizontal section thereof on the line 2—2 of Fig. 1;

15 Fig. 3 is a vertical transverse section on line 3—3 of Fig. 1.

Referring in detail to the drawings, the furnace consists of side walls 10 and 12, end walls 11 and 13 and a roof 14 all formed of suitable refractory material. The furnace 20 proper is supported by a frame work comprising uprights 16 and 18 on opposite sides which are tied together by suitable cross beams 20 and cross bracing 22. An outer shell 24 made of steel plates or the like is 25 supported by the frame work and to this is secured cast iron supporting brackets 26 having inwardly extending flanges 28 which carry the furnace walls.

30 The fixed part of the furnace is open at the bottom from end to end and a novel form of hearth is provided. The arrangement is such that the work to be treated is placed on the hearth at one end and carried through the entire length of the furnace 35 without being disturbed and is discharged at the opposite end thereof.

This hearth comprises a series of conveyor flights 30 which are secured at their outer ends to chains 32 and 34 which latter are 40 trained around suitable sprockets 36 and 38 carried by the shafts 40 and 42. The shaft 42 also carries a sprocket 44 which is connected by means of chain 46 to a shaft 48 which is driven through suitable reduction 45 gearing enclosed in the housing member 50 by a variable speed motor 52. The flights 30 collectively constitute a travelling hearth. Each flight is formed with a depressed center as indicated at 54 and they are also provided with guide portions in the form of 50 grooves 56 and 58 on the outer and inner sides, respectively. The flights may be of cast iron, cast steel or various other metal alloys. Or they may be made of suitable refractory material or of suitable metal cov-

ered or impregnated with a refractory material.

Water cooled supporting skids 60 are adapted to support the upper run of the hearth in a substantially horizontal plane. 60 These water cooled skids are carried by cross members 62 which at their ends rest on filler blocks 64 carried by longitudinally extending channels 66 secured to the furnace frame members. The water cooled skids 60 relieve 65 the chains of the weight of the flights and the weight of the work carried by the hearth and by their coaction with the grooves 58 also prevents any appreciable amount of lateral displacement of the hearth. The 70 lower run of the hearth is supported by a series of idler wheels 68 carried on suitable cross shafts 70. These idler wheels as shown in Fig. 3 are curved in cross-section and spaced so as to register with the curved 75 grooves 56 formed in the flights. Located between certain of the idlers are provided emergency skids 72 which are adapted to form a support for the lower run of the conveyor in the event of damage to the 80 idlers. These supports also serve to support the lower run of the hearth while assembling the same.

The furnace is heated by means of a series of oppositely disposed burners 74 and 76 85 which are supplied with high pressure gas or other suitable fuel from the mains 78 and 80. Flues 82 and 84 located on opposite sides of the furnace are provided for the escape of the spent gases. 90

In operation articles *w* to be heated in the furnace are placed on the traveling hearth, at the left side in Figs. 1 and 2. The drive is such that the hearth is driven in the direction of the arrow X. This carries 95 the work through the furnace at a rate of speed determined by the setting of the controller for the variable speed motor 52. The length of the furnace is such that the time of treatment within the furnace is readily 100 varied to suit different requirements. The sprockets which support the right end of the hearth are located beyond the end of the furnace proper. As the work reaches this end of the hearth it is dropped over the 105 end of the same onto a discharge chute 86.

Though we have described quite specifically the embodiment of the invention illustrated, it is not to be construed that we are limited thereto since various modifications 110

may be made by those skilled in the art without departing from the invention as defined in the appended claims.

What we claim is:—

5. 1. A heating furnace having an endless travelling hearth comprising spaced chains having cross flights secured thereto, and cooled means for supporting said flights independently of said chains.
10. 2. A heating furnace having an endless travelling hearth comprising spaced chains having cross flights secured thereto, said flights having guide portions to prevent lateral displacement thereof and members co-acting with said portions for supporting said flights.
15. 3. A heating furnace having an endless travelling hearth comprising spaced chains having cross flights secured thereto, said flights having grooved portions and guide members coacting with said grooves to prevent lateral displacement of the flights.
4. A heating furnace having an endless travelling hearth comprising spaced chains having cross flights secured thereto, said flights being formed with a central work supporting depressed portion.

In witness whereof, we have hereunto signed our names.

HERBERT C. RYDING.
ARTHUR B. HASWELL.
